TELEVISION PROGRAM SCHEDULE HOLDER

William E. Kling, Detroit, Mich.

Filed May 22, 1959, Ser. No. 56,027

Term of patent 3½ years

(Cl. D1—9)

Fig. 1

Fig. 2

Fig. 3

Fig. 4

Fig. 5

FIG. 1 is a top plan view of a television program schedule holder showing my new design;

FIG. 2 is a front elevational view thereof;

FIG. 3 is a rear elevational view thereof;

FIG. 4 is a side elevational view of the same; and
FIG. 5 is an enlarged bottom perspective view taken
from the rear and one side thereof.

I claim:

The ornament design for a television program schedule
holder, as shown.
